CLAIM

The ornamental design for a spotting scope, as shown
and described.

DESCRIPTION

FIG. 1 is a left side, elevational view of a spotting scope
illustrating my new design;

FIG. 2 is a top plan view thereof;

FIG. 3 is a bottom plan view thereof;

FIG. 4 is a right side, elevational view thereof;

FIG. 5 is a front elevational view thereof; and

FIG. 6 is a rear elevational view thereof.

*Fig. 1.**Fig. 2.**Fig. 3.**Fig. 4.**Fig. 5.**Fig. 6.*
